ADVERTISING FRAME FOR A LIQUID POURER

Filed Oct. 12, 1933

UNITED STATES PATENT OFFICE

1,970,798

ADVERTISING FRAME FOR A LIQUID POURER

John J. Daly and Beatrice Alberdi, New York, N. Y.; said Alberdi assignor to Dalynip Pourer Corp., New York, N. Y., a corporation of New York

Application October 12, 1933, Serial No. 693,234

6 Claims. (Cl. 215—79)

This invention relates to new and useful improvements in a liquid pourer.

The invention has for an object the construction of an article as mentioned which is characterized by a bottle stopper provided with a pouring spout, and advertising buttons mounted upon the pouring spout in a novel fashion.

Still further the invention contemplates the arrangement of a frame mounted upon the side of the spout and a member supported on said frame for supporting said buttons.

Still further this invention contemplates the provision of a plate to comprise said member, said plate to be equipped with an opening through which said advertising buttons may be supported.

Furthermore as another object of this invention it is proposed to provide an air tube in conjunction with the pouring spout and to arrange the tube as to constitute the frame for supporting the support plate which in turn supports the advertising buttons.

As another object of this invention it is also proposed to provide an arrangement whereby the support plate may be removably held in position when the advertising buttons are engaged thereon.

Still further the invention proposes the construction of an article as mentioned which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a side elevational view of a liquid pourer constructed according to this invention.

Fig. 2 is a plan view of Fig. 1 but illustrated with the advertising buttons removed, this view being as though looking in the direction of the line 2—2 of Fig. 1.

Fig. 3 is a horizontal sectional view as though taken on the line 3—3 of Fig. 1 but illustrated with the advertising buttons removed.

Fig. 4 is a vertical sectional view taken on the line 4—4 of Fig. 2.

Fig. 5 is a view similar to Fig. 4 but illustrating another embodiment of the liquid pourer.

Fig. 6 is a side elevational view of a still further embodiment of the liquid pourer constructed according to this invention.

Fig. 7 is a plan view of Fig. 6, this view being

seen as though looking in the direction of the line 7—7 of Fig. 6.

Fig. 8 is a sectional view taken on the line 8—8 of Fig. 9.

Fig. 9 is a vertical sectional view taken on the line 9—9 of Fig. 7.

Fig. 10 is a side elevational view of another type of liquid pourer.

Fig. 11 is a plan view of Fig. 10 seen as though looking in the direction of the line 11—11 of Fig. 10.

Fig. 12 is a sectional view taken on the line 12—12 of Fig. 11.

Fig. 13 is a view similar to Fig. 1 but illustrating another embodiment of the invention.

Fig. 14 is a horizontal sectional view taken on the line 14—14 of Fig. 13.

Fig. 15 is a vertical sectional view taken on the line 15—15 of Fig. 13.

The liquid pourer according to this invention comprises a bottle stopper 10 adapted to be engaged in the neck of a bottle. A pouring spout 11 extends through the stopper 10 from the bottom edge thereof and projects materially above the top. This spout 11 is slightly bent laterally so as to aid in its pouring ability.

A frame 12 (or tube as hereinafter explained) is mounted upon the side of the spout 11 and is adapted to hold a support plate 13 in turn adapted to hold advertising buttons 14. The frame 12 in addition to merely being a frame constitutes a tube which also extends through the stopper 10 and terminates at the end 15 materially below the bottom of the stopper.

The purpose of this tube is to provide for the passage of air from the atmosphere into the bottom. The exceptional length of this air tube is for the purpose to extend above the liquid through the spout 11.

A collar 16 is mounted upon the upper end of the air pipe 12 and hingedly supports a cover 17 for the spout 11. This cover is so arranged that normally it closes the end of the spout, but when the bottle is inclined during the pouring of the liquid due to gravity this cover swings to an open position to allow the passage of the liquid through the spout 11 from the bottle, and air through the tube or into the bottle.

The support plate 13 comprises merely a plate which is placed between the air tube 12 (or frame) and one side of the spout 11. This plate may be held in place by solder, brazing or other similar arrangements.

The plate 13 is provided with a central opening 18 and the advertising buttons 14 are adapted to be secured upon the plate by reason of this 110

opening. In Fig. 15 a detail is shown of the manner in which the advertising buttons are engaged upon the plate. It should be noticed that a pair of these buttons are used, on opposite sides 5 of the plate, one of these buttons being provided with a small projection through the opening engaging the other button. The construction is of the snap type so that the buttons may be snapped in place and removed similarly from place. A 10 cotter pin 19 is shown engaged upon the free end of the air tube 12 clamped upon the collar 16 and constitutes a hinge for the cover 17.

In Fig. 5 another embodiment of the liquid pourer has been disclosed which is very similar 15 to the preferred form and corresponding parts may be recognized by the identical reference numerals. This type of pourer distinguishes in the provision of a frame 12'. It is merely of a different shape than the frame so as to be 20 adapted to accommodate the buttons 14' distinguishing from the buttons 14 also in shape.

More particularly the buttons 14' are of elliptical shape and the frame 12' correspondingly shaped. A further distinction comprises the arrangement of the cover 17, which is equipped 25 with soft material 20 or other similar packing material adapted to engage against the upper end of the spout 11 so as to tightly hold the spout closed under the pressure of a spring 21 coaxially arranged upon the pivot 22 holding the cover 30 17 pivotally.

More particularly the pivot 22 works between a pair of lugs 23 projecting from the sides of the collar 16. The cover 17 is provided with a 35 rear projection 24 by which it may be manually tilted to force it into the open position. This particular type of cover is adapted for bottles containing liquid with gases to prevent the free escape of such gases.

In Figs. 6-9 inclusive, another modification of 40 the invention has been disclosed in which the liquid pourer comprises a large tube 25 extending through the bottle stopper 26. A partition 27 extends completely through the large tube 25 45 dividing it into two longitudinal passages. The side of the tube 25 is formed with several apertures 28 for the passage of the liquid into one of said passages. This tube 25 extends materially below the bottom of the stopper 26 so as to 50 extend above the liquid level in a bottle. Thus the air may pass inwards from the atmosphere through one passage while the liquid may enter the openings 28 and pass outwards through the other passage. A pin 29 projects from one side of the upper end of the tube 25 and constitutes 55 a rest whereby the liquid pourer may be rested against the edge of a glass or other receptacle for the purpose of steadyng the pourer during the pouring operation.

Still further the liquid pourer is provided with 60 a frame 30 attached upon one side of the top portion of the tube 25. This frame is provided with an internal peripheral groove 31. A support plate 32 is arranged within this groove. This support 65 plate comprises a pair of sections in edge alignment with each other and hingedly connected by pins 33 at the contacting edges. The sections comprising the support plate 32 are in the same plane, this corresponding with the extended position of the plate, and the plate is then maintained within the groove. The mounting of buttons 14 upon the sides of the support plate 32 hold 70 the support plate 32 in the latter mentioned condition, (the extended position). The support plate is provided with a central opening 18 for

the coacting elements of the buttons to pass. A feature of this arrangement lies in the fact that upon removal of the buttons 14, the support plate 32 may be bent and removed and then the frame 30 may be used as a ring or handle through which the finger may be engaged for supporting the device or for other purposes.

In Figs. 10 and 12 inclusive another modified form of the invention has been disclosed which is substantially identical to the form shown in 85 Figs. 6-9 inclusive except for the provision of the frame which supports the advertising buttons. The corresponding parts may be recognized by the same reference numerals. Attention is called to the fact that a headed element 90 29' is provided as constituting the stop for resting the stopper upon the edge of a glass or other element.

In Figs. 13-15 inclusive another arrangement 95 of the invention has been disclosed which is very similar to the form illustrated in Figs. 1-4 inclusive except for the construction of the frame which holds the advertising buttons. More particularly a tube 12' extends through the stopper 10 and runs along the side of the spout 11 the 100 entire distance. A branch tube 12a is arranged upon the side of the tube 12' and constitutes the frame for supporting the plate 13 which in turn supports the buttons 14. The feature of this arrangement lies in the fact that the air has a 105 double passage a part of the way from the atmosphere into the bottle. That is, it may pass either completely along the entire length of the tube 12' or may shunt a portion of the tube 12' by passing through the tube 12a instead.

While we have shown and described the preferred embodiment of our invention, it is to be understood that we do not limit ourselves to the precise construction herein disclosed and the right is reserved to all changes and modifications 115 coming within the scope of the invention as defined in the appended claims.

Having thus described our invention, what we claim as new, and desire to secure by United States Letters Patent is:—

1. An advertising frame for liquid pourer, comprising a liquid pourer consisting of a bottle stopper and a pouring spout therethrough, a frame mounted upon one side of said spout, a support plate within said frame, and advertising buttons mounted upon said support plate.

2. An advertising frame for liquid pourer, comprising a liquid pourer consisting of a bottle stopper and a pouring spout therethrough, a frame mounted upon one side of said spout, a support plate within said frame, and advertising buttons mounted upon said support plate, said pouring spout extending from the bottom of the stopper outwards and said frame comprising a tube extended through the stopper from a point 130 materially below the stopper to the top of the 135 pouring spout.

3. An advertising frame for liquid pourer, comprising a liquid pourer consisting of a bottle stopper and a pouring spout therethrough, a frame mounted upon one side of said spout, a support plate within said frame, and advertising buttons mounted upon said support plate, said frame comprising a tubular member for the passage of air from the atmosphere into the bottle.

4. An advertising frame for liquid pourer, comprising a liquid pourer consisting of a bottle stopper and a pouring spout therethrough, a frame mounted upon one side of said spout, a support plate within said frame, and advertising buttons mounted upon said support plate, said

support plate being fixed within said frame on the side of said spout.

5. An advertising frame for liquid pourer, comprising a liquid pourer consisting of a bottle stopper and a pouring spout therethrough, a frame mounted upon one side of said spout, a support plate within said frame, and advertising buttons mounted upon said support plate, said support plate being provided with an opening, and 10 said advertising buttons being arranged on opposite sides of said plate and equipped with inter-engaging means extending through said opening for the mounting of the advertising buttons in place.

6. An advertising frame for liquid pourer, comprising a liquid pourer consisting of a bottle stopper and a pouring spout therethrough, a frame mounted upon one side of said spout, a support plate within said frame, and advertising buttons mounted upon said support plate, said support plate comprising a pair of sections hingedly connected and in aligned position having their edges extending into an internal groove in said frame, and said advertising buttons holding said sections in aligned positions.
